UNITED STATES PATENT OFFICE.

FRANK HARRISON HARRIS, OF TOLEDO, OHIO:

DESIGN FOR A CAR-PLATFORM.

SPECIFICATION forming part of Design No. 31,374, dated August 8, 1899.

Application filed July 17, 1899. Serial No. 724,199. Term of patent 14 years.

To all whom it may concern:

Be it known that I, FRANK HARRISON HARRIS, a citizen of the United States, residing at Toledo, in the county of Lucas and State of Ohio, have invented and produced a new and original Design for a Car-Platform, of which the following is a specification, reference being had therein to the accompanying drawings, in which—

10 Figure 1 is a perspective view of the car-platform, and Fig. 2 is a front elevation.

The platform in its entirety has the appearance of a flat rectangular body A, with uprights B and C projecting upward in parallel planes from each of its ends, as shown. On each side of the body and depending from the edge B' thereof are two downwardly-extending projections D and E, placed at some distance apart, and each projection is provided 15 with a central rectangular opening C'. F and F' designate circular apertures in the projections upon opposite sides of the central opening in the latter.

20 The platform is provided with reduced rectangular portions G G' at its ends, and depending from the side of each of said portions

is a strip of material in the shape of a flight of steps H, as shown.

In appearance the uprights upon the platform resemble oppositely-arranged U-shaped sections, the sides I I' thereof extending inwardly toward the center of the platform and in the same planes with the platform edges B'. The connecting-plates J J' of the sections extend across the ends of the platform 35 and are provided with rectangular extensions K K'. In each of said latter extensions is formed an arch-shaped opening L L'.

The leading feature of my design resides in the platform of rectangular configuration 40 provided at its opposite ends with oppositely-arranged sections, substantially U-shaped in configuration.

What I claim is—

The herein-described design for a car-plate 45 form, as herein shown.

In testimony whereof I affix my signature in presence of two witnesses.

FRANK HARRISON HARRIS.
